CHIMNEY TOP

Karl Kroebig, Milwaukee, Wis.

Application January 24, 1930, Serial No. 423,073

3 Claims. (Cl. 98—66)

This invention relates to chimney tops.

The chimney top to which the invention applies in particular is employed to increase the draft of a chimney and has a flue which forms an extension of the chimney flue.

An object of the invention is to increase the draft of a chimney and to prevent down drafts therein irrespective of the direction of the wind or the proximity of adjacent structures.

Another object is to direct currents of air upwardly and over the flue.

Another object is to provide a chimney top which may be readily and economically manufactured and installed.

According to the invention, the outside of the chimney top is provided with inclined channels to direct currents of air upwardly and over the upper end thereof.

The chimney top may also be provided with small channels to direct currents of air upwardly and into the top of the flue.

Chimney tops embodying the invention are shown in the accompanying drawing in which the views are as follows:

Fig. 1 is a top plan view of a chimney top;

Fig. 2 is an elevation of the chimney top shown in Fig. 1; and

Fig. 3 is a central vertical section of a chimney top embodying a modification of the invention.

The chimney top has a continuous side wall 1 which normally rests upon the top of a chimney and provides a flue 2 in alignment with the flue of the chimney and forming an extension thereof.

If the chimney is provided with a flue lining, the same extends into the flue 2 and holds the chimney top against lateral movement, as shown in dotted lines in Fig. 3.

The chimney top is preferably made from moldable material, such as concrete, and may consist of a single unit, as shown in Fig. 2, or be formed of interlocking sections, as shown in Fig. 3.

The side wall 1 is thicker at the bottom than at the top, and the outer faces thereof slope upwardly and inwardly to deflect horizontal currents of air upwardly and over the top of the flue 2.

Each of the outer faces of the wall 1 is provided with two wind deflectors 3 which converge toward the upper end of the chimney top and form a channel 4 between the same.

The outer edges of the deflectors 3 are vertical, so that the channel 4 is both deeper and narrower at the top than at the bottom thereof.

The wind deflectors 3 prevent the air in a

channel 4 from spreading laterally and the wind pressure upon that channel causes the air therein to move upwardly at an increased rate as the channel narrows and to pass over the top of the wall 1 with sufficient force to deflect the horizontally moving currents of air and create a low pressure area at the top of the flue 2.

If the chimney is located adjacent a high structure, so that the wind deflected thereby would ordinarily cause down drafts in the chimney, the air deflected upwardly in the channels 4 has sufficient force to overcome such down drafts and maintain the draft of the chimney.

The chimney top may also be provided with secondary channels 5 which are formed in the top of the wall 1 to direct small currents or jets of air upwardly into the top of the flue 2.

The wind pressure upon the air in a channel 4 causes air to move through the small secondary channels 5 at a relatively high speed and materially assist in maintaining the draft of the chimney.

The wind deflectors 3 adjacent each corner of the chimney top are joined to each other by an arcuate face 6 and form a shallow channel 7 therebetween which slopes upwardly and inwardly to direct a current of air upwardly and over the corners of the flue 2.

The channels 7 assist the channels 4 in directing currents of air over the top of the flue 2 whenever the wind is not blowing squarely into a channel 4.

The chimney top has been shown as being rectangular in cross-section, but the invention is not limited to that specific form and is susceptible of various modifications without departing from the scope thereof as hereafter claimed.

The invention is hereby claimed as follows:

1. A draft increasing chimney cowl, comprising a body having the shape of a frustum of a pyramid provided with a flue extending therethrough, two wind deflectors formed upon each side wall of said pyramid perpendicular thereto and converging inwardly toward the top forming an upwardly and inwardly inclined converging channel therebetween to turn the wind and direct an accelerated current of air upward over the flue, and a secondary channel formed in the top of each side wall and inclined inwardly and upwardly to deflect a jet of air from the main channel across the top of the flue in upwardly inclined direction to increase the draft through the flue.

2. A chimney top provided with a pyramidal exterior and having a flue extending there-

through, two wind deflectors arranged upon each side of said pyramidal exterior at substantially right angles thereto and converging toward the vertex of said pyramidal exterior to form with the face of the pyramidal exterior a converging channel of rectangular cross-section to direct currents of air over said flue.

3. A chimney top provided with a pyramidal exterior and having a flue extending there-
10 through, one side of said pyramidal exterior hav-

ing a channel extending therethrough on the edge thereof adjacent the vertex of said pyramidal exterior having a slope slightly greater than said side and forming a means to direct air over said flue, a plurality of deflectors arranged on the sides of said pyramidal exterior to direct air over said flue and through said channel.
